UNITED STATES PATENT OFFICE.

CHARLES J. NASH, OF CHICAGO, ILLINOIS, ASSIGNOR TO UNIVERSAL DRAFT GEAR
ATTACHMENT CO., OF CHICAGO, ILLINOIS, A CORPORATION OF ILLINOIS.

DRAFT-RIGGING FOR CARS.

1,192,096.

Specification of Letters Patent. Patented July 25, 1916.

Application filed September 23, 1914. Serial No. 863,062.

To all whom it may concern:

Be it known that I, CHARLES J. NASH, a citizen of the United States, and resident of Chicago, county of Cook, and State of Illinois, have invented certain new and useful Improvements in Draft-Rigging for Cars, of which the following is a specification, and which are illustrated in the accompanying drawings, forming a part thereof.

10 The invention relates to mechanisms for transmitting pulling and buffing stresses to the underframing of a car; its object being to secure great strength while avoiding excessive weight or complicated constructions 15 and operations.

An embodiment of the invention is illustrated in the accompanying drawings, in which—

Figure 1 is a detail longitudinal vertical section of the underframing of a car and of the draft rigging on the center line of draft; Fig. 2 is a detail plan view of the same, partly in section; and Figs. 3 and 4 are transverse sectional views on the lines 25 3—3 and 4—4, respectively, of Fig. 2.

A pair of center sills is shown at 10, 10; an end sill at 11, and a buffer plate at 12.

The coupler is represented at 13. The coupler extension takes the form of a yoke 30 comprising longitudinal side members 14, 15, a shell or casing 16 for inclosing the cushioning elements, and a rear end 17 reinforced by a transverse buffing boss 18. The side members 14, 15, of the coupler extension are slotted, as shown at 19, to receive a key 20, which also passes through a suitable transverse slot in the shank of the coupler 13 and through elongated slots, as 21, in the sills 10 and in the draft plates 22 affixed thereto. The draft plates 22 are provided with buffing lugs 23, 24, against which the buffing boss 18 of the coupler extension normally bears. The casing 16 of the coupler extension rides upon a carrier plate 25 which 45 is bolted to the sills 10.

The device is shown as applied to the so-called twin spring type of gear, wherein a pair of springs located side by side and acting in multiple is employed. The casing 50 is accordingly designed to properly house and hold in place such pair of springs, and may, of course, be differently shaped when

the cushioning or shock-absorbing elements are of different form.

The springs are shown at 26, 27, and are 55 housed within the casing 16 and react between its rearward wall 17 and a bearing block 28, against the forward face of which the inner end of the shank of the coupler 13 bears. The block 28 is cored out to reduce 60 its weight, without detracting materially from its strength, and comprises front and rear plates 29, 30, and connecting webs 31, 32, 33, the last-named being located on its median horizontal plane and being slotted to 65 receive a key 34, which extends through elongated slots 35 in the side members of the coupler extension, and similar slots 36 in the draft plates 22.

When the parts are assembled the springs 70 26, 27, hold the key 34 at the forward ends of the slots 35, 36, the key 20 at the forward ends of the slots 19, and the buffing boss 18 in engagement with the buffing shoulders 23, 24. Under draft stresses the coupler extension 75 is drawn forward, the key 20 sliding in the slots 21, the rear end of the extension compressing the springs against the block 28, which transmits the stresses through the key 34 to the draft plates. In buffing the 80 coupler 13 moves inward, the key 20 traveling in the slots 19 and 21, the block 28 and key 34 being forced backwardly, the springs being compressed against the rearward end 85 of the coupler extension and the stresses being transmitted through the bearing boss 18 to the buffing shoulders 23, 24.

I claim as my invention—

In a draft rigging, in combination, a pair 90 of slotted draft plates having buffing abutments, a coupler extension comprising a spring-inclosing casing engageable with the buffing shoulders and open at its forward end, a bearing block normally forward of and slidable within the open end of the casing, a spring housed within the casing and reacting between the inner end thereof and the bearing block, and a key set through the block and slots in the draft plates.

CHARLES J. NASH.
